UNITED STATES PATENT OFFICE.

BENJAMIN F. OREWILER, OF CHICAGO, ILLINOIS.

ATTACHMENT FOR CONNECTING TAPE-SECTIONS.

1,191,723.

Specification of Letters Patent. Patented July 18, 1916.

Application filed May 3, 1915. Serial No. 25,591.

To all whom it may concern:

Be it known that I, BENJAMIN F. OREWILER, a citizen of the United States, residing at Chicago, in the county of Cook and State of Illinois, have invented certain new and useful Improvements in Attachments for Connecting Tape-Sections, of which the following is a specification:

The present invention relates to a metal piece or part adapted and arranged for the purpose of connecting the elastic and non-elastic sections of a garter or similar garment-supporting device.

One of the objects of the invention is to bring about the joining of the elastic and non-elastic sections without the puncturing of the elastic section by sewing or otherwise.

A further object of the invention is to provide a piece or part of the character described, which is cheap and simple of construction and easy of application.

The invention further consists in the features of construction and combination of parts hereinafter described and claimed.

In the drawings: Figure 1 is an elevation of a garter appliance equipped with the attachment of the present invention; Fig. 2, an enlarged section taken on line 2-2 of Fig. 1, and Fig. 3, an enlarged section taken on line 3-3 of Fig. 1.

In the art to which the present invention relates, considerable difficulty has been experienced by manufacturers in properly joining the elastic and non-elastic tapes which are portions of garment supporting devices. It is highly undesirable, in connecting elastic and non-elastic tapes, to puncture the elastic tape by stitching or the use of penetrating points, since this severs the elastic strips, causing a shrinkage of them within the channels of the fabric in which they are confined, resulting in a loss of elasticity in a certain portion of the tape and decreases its efficiency; and it is, moreover, very advantageous to join the elastic and non-elastic tapes with very little, if any, overlapping of the elastic tape, since this elastic tape is expensive and each fraction of an inch saved in the process of manufacture, results in a substantial saving when manufacturing on a large scale is taken into consideration. In the present invention, a device is provided for joining the elastic and non-elastic sections of a garment sup-

porter in a manner to overcome the objections noted above.

Referring now to the drawings: The appliance of the present invention is shown as applied to a garter consisting of a section of elastic tape 4, depending from which are companion sections of non-elastic tapes 5, each of which may be separate or may be of one continuous piece, as desired. In the construction illustrated, it is shown as one continuous strip; it is to be understood, however, that the appliance of the present invention is not limited to use with a non-elastic section of 2 tapes, but may be employed with a non-elastic section of a single tape. The elastic section 4 is provided at its upper end with any suitable form of securing device 6, and said section is further provided with an adjusting buckle 7 which may be also of any suitable form. Connected to the non-elastic section 5, are garment clasps 8 consisting of the usual stud 9 carried by a base plate 10 and a clamping member 10^a formed with the usual button-hole slot, although, of course, the particular form of garment clasp may be varied, so far as the present invention is concerned.

The present invention deals with the part or piece which connects the elastic section 4 with the non-elastic section 5 and, as will be seen from the drawings, said part or piece consists of a body 11 formed, as shown, of a single piece of metal which is bent back upon itself midway its length, as at 12, whereby said body is formed to constitute a front section 13 and rear section 14. The front section is formed with a slot 15 and the rear section with an inwardly turned, preferably serrated, flange 16, which, as will be seen from Fig. 2, is in alignment with the slot 15. The member 11 is also formed with a slot 17 at the point where it is bent.

In use, the strap of the elastic section 4 is inserted between the front section 13 and rear section 14 of the member 11, it being understood that the rear section 14 is initially bent backward and away from the front section 13 a sufficient distance to allow of the insertion of the tape sections to be joined. After the elastic section has been inserted, as described above, the non-elastic section is passed through the slot 17 in the member 11 and is brought up over the top edge of the rear section 14 and thence passes

2
along the back of this section. By this arrangement it will be seen that the metal at the back of section 11 is covered up. This is highly important in devices of this character, since it is impractical in the trade to offer any attachment not of the so-called rustless character—that is, having a fabric backing for all of the metal parts.

After the elastic and non-elastic sections 10 have been placed in position, as aforesaid, the rear section 14 is pressed or swaged toward the front section 13, with the result that the edge 16 of the rear section will press or force the tape sections into the slot 15, so that they are wedged therein, as shown in Fig. 2, and are thus securely and efficiently held in position.

From the foregoing, it will be readily understood that attaching these sections in the 20 manner described effects no puncturing of the elastic section in any manner, but gives a firm and rigid union between the elastic and non-elastic tape sections without the objectionable puncturing of the elastic section.

25 I claim:

1. An attachment for connecting tape sections, comprising a metallic one-piece body 30 bent to U-shaped formation, to provide a front section and a rear section, a horizontal recess formed in the front section, an inwardly extending flange on the upper end of the rear section alined with said recess, the space between the front and rear sections forming a pocket for the reception of 35 the ends of tape sections, one tape section extending upward from said pocket along the rear of the front section, the other tape section extending from said pocket across

the upper edge of the rear section, thence 40 downward and across the back of said section, whereby a fabric covering for the back of the attachment is provided; and said rear section, when swaged toward the front section, forcing said tapes lying opposite said 45 flange into said recess to maintain the tape sections in fixed relation to one another, substantially as described.

2. An attachment for connecting tape sections, comprising a one-piece metallic body 50 bent to U-shaped formation to provide a front section and a rear section, said front section having formed therein a transversely extending recess, an inwardly extending flange on the upper end of the rear section alined with said recess, the space between the front and rear sections forming a pocket for the reception of tape sections, 55 said body being formed with a slot in the wall connecting the front and rear sections, one tape section extending from said pocket across the rear face of the front section, the other tape section extending from a point beyond said attachment through the slot 60 and into the pocket, thence across the top edge of the rear section, and thence across the back of the rear section to a point beyond the attachment, whereby a fabric covering for the back of the attachment is provided, and said rear section when swaged 65 toward the front section forcing said tapes lying opposite said flange into said recess to maintain the tape sections in fixed relation to one another, substantially as described.

BENJAMIN F. OREWILER.
